UNITED STATES PATENT OFFICE.

S. DENVER ROBERSON, OF ST. LOUIS, MISSOURI.

STREET-INDICATOR.

1,342,394.

Specification of Letters Patent.

Patented June 1, 1920.

Application filed August 26, 1919. Serial No. 319,859.

To all whom it may concern:

Be it known that I, S. DENVER ROBERSON, a citizen of the United States, residing at St. Louis, State of Missouri, have invented new and useful Improvements in Street-Indicators, of which the following is a specification.

This invention relates to improvements in street or station indicators and one of the 10 objects of the invention is to provide means, automatically operated, for notifying the occupants of a car the name of the next street or station at which the car will stop.

Another object of the invention is to provide 15 electric means for actuating the device with means for moving the same into operative position by contact devices placed at any desired point on the conductors for supplying current for the car.

The invention also consists in certain 20 other features of construction and in the combination and arrangement of the several parts, to be hereinafter fully described, illustrated in the accompanying drawings and specifically pointed out in the appended 25 claim.

In describing my invention in detail, reference will be had to the accompanying drawings wherein like characters denote 30 like or corresponding parts throughout the several views, and in which:

Figure 1 is a face view of the casing which contains the actuating mechanism forming my invention.

Fig. 2 is a cross sectional view through 35 the case.

Fig. 3 is a horizontal section taken longitudinally through the case.

Fig. 4 is a detail view of the notched 40 wheel with its slide.

Fig. 5 is a view showing one end of the feed roller with a notched wheel thereon.

In these views 1 indicates a case which is 45 adapted to be secured in position in a car where its front side will be in full view of the occupants of the car. This front face is provided with an opening 2 through which the indicia on the strip carried by the rollers within the casing, will appear.

Above this opening may be printed the legends which coöperate with the indicia on the strip to give the passengers the information desired. The strip 3 is supported on the upper and lower rollers 4, the shafts of 50 which are suitably journaled in the casing. The strip is carried across said opening 2

by means of the guide roller 5. The shafts 4' of the rollers 4 carry the beveled gears 7 which are adapted to mesh with the gears 8 on the shaft 9. This shaft 9 is adapted 60 to have longitudinal movement so as to move one or the other of the gears 8 into mesh with one or the other of the gears 7 whereby the strip will be moved in one direction or the other. The shaft 9 is provided 65 with a pulley 10 which is connected with a pulley 11 by a belt 12. The pulley 11 is carried by a shaft 13 and this shaft has secured thereto a large wheel 14. This wheel 14 is connected to a pulley 15 by the belt 70 16 and this pulley 15 is connected with the shaft of a motor 17. This motor is driven from the current supply to the car and I prefer to connect the wires 18 of this motor with a plug 19 so that the plug may 75 be inserted in any one of the electric light sockets of the car. When desired, a transformer 20 may be connected with the wires of the motor.

It will thus be seen that when the motor 80 is operated the shaft 9 will be rotated by means of the wheels and belts described so that one or the other of the rollers 4 will be turned to wind the strip thereon so that the indicia on said strip will be brought 85 before the opening 2 in the case.

As the object of my invention is to notify the passengers of the name of the next street or station at which the car will stop, I provide means for holding the parts stationary 90 until the street or station is passed and then the parts are moved to bring the name of the next street or station into view and to hold it in this position until this station or street is passed. The means for giving the 95 parts this starting and stopping motion comprises the electromagnets 21, the coils of which are connected by the wires 22 with the contact device 23 which is carried by the trolley pole 24 of the car. This device 100 23 is adapted to contact with the trips 25 which may be placed at any desired points on the conductor 26. In this way as soon as the device strikes the trip 25, current will flow through said parts and the wire 22 to 105 the coils of the magnet so that the armature 27 will be attracted. This movement of the armature will close the switch 28 to which the wires 18 of the motor 17 are connected so that current will be supplied to said motor and the parts set in motion. The means for holding the switch closed for a limited 110

time after the current is broken by the device passing the trip 25, consists of a wheel 29 located on the shaft 5' of the roller 5 and which is provided with a notch 30. 5 When the parts are in operative position the end of the armature lies in this notch as the spring 31 forces the end of the armature upwardly against the periphery of the wheel 29 and when the notch comes opposite said end the armature will enter said notch. As long as the armature is out of the notch, the switch 28 will be closed so that the motor is actuating the parts and this movement will continue until the wheel 15 29 has made a complete revolution and the notch is brought into engagement again with the end of the armature.

In order to prevent the armature from reengaging the notch before the motor begins to actuate the parts, I provide a slide 32 on the wheel 29. This slide is formed 20 of thin spring metal and is provided with a projection 33 extending into the notch. The end of the slide, beyond the projection, has 25 a beveled edge 34 and springs 35 tend to hold the slide with the projection at the open end of the notch and the portion with the beveled edge projecting beyond the periphery of the wheel. When the wheel is in 30 normal position, however, or with its notch in position to receive the armature, the slide is held with its lower end flush with the periphery of the wheel by the spring dog 32' engaging the upper bent end of the slide. In this position the projection 33 will be in the bottom of the slot and the end of the slide will bridge the notch so as to prevent the armature from entering the notch. The armature when in the notch will 40 bear against the slide and hold its end a slight distance away from the face of the wheel so that as the armature leaves the slide the end of the slide will spring back into engagement with the face of the wheel 45 with its end edge preventing the armature from returning to the notch. After the wheel has begun to revolve the bent end of the slide will leave the dog so that its springs 35 will move the slide to a position with 50 its end projecting beyond the periphery of the wheel and the projection 33 adjacent the open end of the notch. When the wheel has made a complete revolution the armature will strike the beveled edge of the projecting part of the slide so as to cause the slide to bend away from the face of the wheel and when the notch comes opposite the armature the spring of the armature will cause the same to enter said notch and by 55 engaging the projection 33 force the slide upwardly past the spring dog and thus return the parts to their normal position.

The means for moving the shaft 9 longi-

tudinally to reverse the direction of movement of the strip or tape, consists of a spring 65 36 on each of the rollers 4 and having its end engaging a notch 37 in the roller. These springs are normally held in their notches by the tape but as soon as the tape is unwound and the springs uncovered they will 70 spring out of their notches. A part on this spring is adapted to strike a slidable rod 38 and move the same longitudinally. This movement of the rod will rock the lever 38' which is pivoted at 38" and which has its 75 other end connected with the shaft 9 so that when the lever is rocked the said shaft will be moved longitudinally. These springs 36 also act to keep the strip or tape 3 under tension.

I provide a push rod 39 for actuating the armature so that the strip or tape may be moved to any desired position to set the device.

It will, of course, be understood that the 85 trip devices 26 may be placed along the track and connected with the conductors where said conductors are located underground.

What I claim is:—

A device of the class described comprising 90 a casing, a pair of rollers journaled therein, a strip connected with said rollers and containing indicia adapted to appear in said opening, an electric motor, means for connecting the same with the rollers to rotate the same, a switch for said electric motor, electromagnetic means including an armature for controlling said switch, track 95 obstructions, means operated thereby for closing the circuit to the electromagnetic means to close the switch, a wheel operatively connected with the motor and having a notch therein, said wheel engaging the armature for holding the switch closed and the notch being adapted to receive the armature to open the switch and a slide member on said wheel for preventing the reengagement of the armature with the notch before the motor begins to rotate, said slide being made of spring material so as to spring under the armature when the same is withdrawn from the notch, spring means 100 for moving the slide outwardly after the wheel begins to rotate, a beveled portion on said slide for engagement by the armature after the wheel makes one revolution to force the slide outwardly to permit the armature to reenter the notch, means for returning the slide to normal position by 105 the armature and a dog for holding the slide in normal position when the wheel is at rest.

In testimony whereof I affix my signature.

S. DENVER ROBERSON.
